DAVID C. KLAUSMEYER AND ROWLAND L. RICKWOOD, OF CINCINNATI, OHIO, ASSIGNEES TO THE CINCINNATI BICKFORD TOOL COMPANY, OF CINCINNATI, OHIO, A CORPORATION OF OHIO.

RADIAL-DRILL COLUMN CLAMP.

Application filed September 15, 1922. Serial No. 588,461.

To all whom it may concern:

Be it known that we, DAVID C. KLAUSMEYER and ROWLAND L. RICKWOOD, each a citizen of the United States, and residing at 5 Cincinnati, in the county of Hamilton and State of Ohio, have invented a new and Improved Radial-Drill Column Clamp, of which the following specification is a full disclosure.

10 Our invention relates to precision machines, especially such as are relatively massive and which normally operate under heavy strains and yet which must, for purposes of adjustment, admit of a free and 15 comparatively delicate manipulation. Machine-tools of the type known as "radial-drills" may to advantage embody all or many of the characteristics of this invention and a typical embodiment of that nature may well be resorted to by way of a 20 full disclosure of this invention.

A radial-drill comprehends a vertical column from which horizontally extends an arm on which, in turn, is supported a so-called "drill-head" in which is journaled the usual vertical spindle that carries the drill-point at its lowermost extremity. These parts are heavy and, through the agency of the customary power-driven elements, the 25 drill-point is urged into the work under very considerable pressure. In consequence, the arm-supporting column should be capable of withstanding very severe bending strains. If not adequately constructed, the 30 column will be caused to deflect or sway back, during the tooling operation, sufficiently to disturb the initial location of the drill-point and thus the accuracy of the work.

One of the difficulties confronting the 35 designer is that it is essential to provide for an adjustment of the arm in a vertical direction along the column and also to provide a second adjustment whereby the arm may be swung in a horizontal plane to bring the 40 drill-point to various lateral positions with respect to the work. This second adjustment necessitates an arrangement whereby the particular member (along which the arm is vertically movable) may be rotated about 45 a vertical axis and ultimately clamped against further movement. The aforesaid member is usually known as a column and it is frequently made tubular in form and 50 mounted to turn about a vertical non-rotat-

able post which extends upwardly through 55 the bore of the sleeve; the two being journaled together at appropriate points to preserve concentricity.

Usually, the inner post and its circumscribing sleeve admit of being clamped together and it has heretofore been generally assumed that such rigidity as exists may be attributed to the combined strength of these two members considered as an integral entity. We have ascertained, however, that 60 the ultimate rigidity is derived to a greater extent than has heretofore been appreciated from the sleeve itself and that the greatest rigidity is attained by clamping the sleeve down upon a rigid platform, rather than by 65 resorting alone to the usual annular clamp against an ordinary cylindrical portion of the post, and that the best results are derived from the cooperation of both species 70 of clamps.

This joint invention, accordingly, undertakes so to form the post and the sleeve, and so to mount the latter on the former, that the two will be locked together more effectively 75 towards attaining a high degree of rigidity 80 and yet, when released by appropriate means, to admit of easy manipulation for purposes of adjustment. In this invention, the sleeve during the tooling-operation has its lower end resting flat-wise upon and 85 clamped downwardly against a rigid platform (which may be a part of the post or of the base proper) and, simultaneously, the upper end of the sleeve has a thrust-bearing 90 operating under considerable pressure 95 against the upper end of the fixed post; whereby at widely separated points the sleeve has a firm support adequate to resist bending strains. In other words, the sleeve becomes virtually transformed into an auxiliary post which is locked to both the upper and the lower end of the main post; resulting 100 in a dual-post of great rigidity. During the period of adjustment, however, the sleeve is merely freely suspended from its upper end and none of its weight, or at least no great portion of its weight, is resting on the annular platform; with the result that no undue frictional resistance must be overcome by the limited strength of the operator when 105 swinging the arm into a different position in its horizontal plane.

Our joint invention will be better comprehended when it is understood that

hended in detail by considering the preferred embodiment thereof depicted by the annexed drawings, of which:—

Fig. 1 is a side elevation of a radial drill embodying this invention. Fig. 2 is a side elevation, partly in section, of the post, the sleeve, and the clamping means; the arm being omitted. Fig. 3 is a plan of the clamping ring. Fig. 4 is a horizontal section through the post and sleeve along the line 4—4 of Figs. 1 and 2. Fig. 5 is a secondary detail of one side of the lower bell-like portion of the sleeve showing the means for adjusting the sleeve into close proximity with a cylindrical clamping surface provided by the lower portion of the post. Fig. 6 is a fragmentary view, partly in elevation and partly in vertical section, of the lower end of the post and sleeve combining 20 the clamp with a special friction reducer.

Referring to Fig. 1, A designates the post which is mounted rigidly on an appropriate base and B indicates a sleeve which, during the period of adjustment, may be rotated 25 about the post. A radial arm C is journaled to the smooth exterior periphery of the sleeve so that it may, when unclamped, freely slide up and down thereon. A drill head D is slidably mounted on the extended 30 portion of the arm so that it may be shifted toward and away from the column and a spindle E is carried thereby. This spindle may be driven, as will be understood, in an appropriate manner by suitable connections 35 deriving power from a main electric motor F mounted either on the base or, as shown, on a short rearward extension of the arm C.

One of the incidental objects of this particular embodiment of this invention is to provide 40 for the raising and lowering of the arm by power derived, independently of the main motor F, from a small auxiliary motor G mounted at the upper end of the sleeve and arranged to rotate a lifting screw in either direction to raise or lower the arm. This motor is controlled by a shaft a which extends vertically along side of the hub C' of the arm and which is actuated by a handle b. The upper end of this shaft operates a 45 switch e for controlling the electric motor G. To prevent the user from turning on the lifting power when the arm C is clamped (by means of the clamps K, K') the levers k, k' have an interlocking relation with 50 squared shaft a in the manner set forth in the patent to Klausmeyer, No. 1,140,903.

Referring to Fig. 2, the post A terminates at its lowermost end in a portion 1 having a flange 2 which, by means of appropriate bolts 3, may be secured rigidly to the base proper. The portion 1 may be surmounted by a somewhat reduced annular portion 4 and the latter, at a suitable point, provides an annular platform 5. The upper horizontal marginal portion 6 of this

flange constitutes an annular seat or shoulder adapted to receive the weight of the sleeve when the latter is forced down upon it by the clamping agent soon to be described.

This post A is tubular in form and it extends upwardly and terminates adjacent the upper extremity of a sleeve B which circumscribes it. This post essentially serves the purpose of a long fixed pivot for the 70 sleeve which essentially is so mounted as to admit of being suspended from its upper end. In a construction of this nature, there are three distinct functions to be attained. First, the sleeve must be maintained accurately in co-axial relation with the post inasmuch as the fundamental precision of the machine depends upon the perfect preservation of this relation. Second, the weight of the sleeve (supplemented by that of the 75 arm, etc.) must be so freely carried that, during the period of adjustment, the user can with ease move the ponderous parts. Third, during the tooling-operation, the sleeve must be clamped firmly in the co-axial 80 relation (accurately determined as aforesaid) so that it will be capable of withstanding for whatever strains are imposed upon it by the tooling-operation. This clamping should primarily effect a very solid resting 85 of the sleeve on its end so that it will virtually become an independent auxiliary post capable of most effectively resisting even the slightest tendency to overturn about its lower end or in any manner to shift its position relative to the stationary central post 90 and, preferably also, it should likewise be clamped around the post to assist further in maintaining its relation to the post. The manner in which these several functions 95 are obtained by this invention will be explained.

The co-axality between the sleeve and the post is accurately insured by a smooth truly-cylindrical lower-bearing 11 provided by the 100 post and a roller bearing 16 interposed between the upper end of the post and the upper end of the sleeve. The suspension of the sleeve is obtained by a thrust-bearing 28 seated upon a shoulder 17 provided by the 105 upper end 14 of the post; said thrust-bearing being adapted to carry the weight of the sleeve as will be presently described. The solid positive seating of the sleeve is attained by a bearing 6 against which the sleeve 110 is depressed and to which it is securely clamped. This bearing also tends to serve the purpose of restraining the sleeve against rotation about the post but, preferably, this function is assisted by an extensive cylindrical surface 9 in the nature of a brake or friction surface provided by the post; the sleeve being split and adapted, by a slight contraction, to be clamped around the same.

It is not desirable to have the sleeve rest 115

- heavily at all times on the platform 6, since it would then be very difficult for the user to swing the arm and sleeve for purposes of adjustment by reason of excessive friction.
- 5 Accordingly, this invention contemplates means for enabling the bearing 6 to be relieved of excessive loads preparatory to make an adjustment. In other words, during such periods, the entire weight, or substantially 10 so, of the sleeve is caused to be carried by an anti-friction thrust-bearing as of the roller type which reduces the friction to a minimum. A simple and effective way of accomplishing that purpose is to interpose a resilient 15 instrumentality between the thrust-roller bearing 28 and either the post A or the sleeve B. Preferably, this resilient instrumentality assumes the form of a flexible diaphragm 29 which is sufficiently stiff 20 to carry substantially the full weight of the arm and yet which permits the arm to be depressed very slightly under the pressure exerted by an appropriate clamp until it is brought into a firm seating relation with the 25 platform 6. It will be understood that this movement need only be very slight; it being only necessary to lift the sleeve barely enough to relieve its actual pressure against 30 the platform 6 in order to free it fully for purposes of adjustment.
- A very simple and durable flexible diaphragm admirably suitable for the purpose is one formed as an integral part of a ring or cap B' which may be made of steel or 35 other suitable material and be permanently affixed to the upper end of the sleeve. For example, the cap B' is shown to consist of an annular rim-like portion having a flange 30 which overlaps and circumscribes the upper 40 end of the sleeve and is securely affixed thereto. A flange-like portion 29 radiates inwardly from the inner periphery of the cap B' and is preferably dished to give it a greater degree of resiliency. This dished 45 diaphragm 29 has a hub 32 which is provided with screw-threads 33 receiving a nut 34 which, in turn, presses directly against the thrust-bearing 28. When the machine is being assembled, the nut 34 is adjusted by 50 means of a spanner-wrench engaging notches 35 in its periphery; the adjustment being carried to the point of insuring that the sleeve will not make undue contact with the platform 6 when the clamps are released.
- 55 The clamping agent M is shown by Fig. 3 and preferably has the form of a split ring comprising sections such as m and m'. This split ring has an interval V-shaped groove 36 adapted to engage conversely flaring conical shoulders 7 and 37 provided by the sleeves and the platform 5, respectively. It is important to note that the chief function of this split-ring is to compel a depression of the sleeve, i. e., to force a movement of said 60 sleeve in a vertical direction to close the gap 65 between the platform 6 and the abutment of the sleeve and cause these parts to press together endwise so firmly as to lock them together at the point 6. Incidentally, it may also accomplish a sufficient contraction 70 of the split clamping portion 38 of the sleeve to prevent any turning of the sleeve about the post, as will soon be described.
- Since the primary function of the split-ring is to effect a movement in a vertical 75 direction of the sleeve, under considerable pressure it is important that the angle subtended by the conical surface 37 shall be such that the vertical component of the pressure exerted by the split-ring shall be materially 80 greater than the horizontal component and, therefore, the angle to the horizontal contemplated by this invention is in the neighborhood of $\frac{\pi}{4}$. Such an angle will enable 85 a great force to be brought in a vertical direction and a materially smaller force in a horizontal direction; the latter being however adequate to effect a constriction of the split portion 38 of the sleeve around the 90 brake drum or cylindrical clamping surface 9.
- From a structural standpoint, the internal V-shaped groove, provided by the split-ring is discontinuous; being composed of sectors 95 39 to 44. This enables the pressures to be exerted radially at diametrically opposite points and insures a uniform action to compensate for any possible irregular deformations of the clamping-ring. The two semi-annular portions m and m' are held together by means of two bolts 45 and 46. The head of bolt 45 preferably has a hemispherical face 47 seated in a corresponding 100 recess in the section m' and a similarly formed nut 48 is likewise adjustably arranged at its other end. This construction provides a desirable hinge-like action. Bolt 46 is a part of a clamping device and preferably is in the nature of an eye-bolt; and an ordinary eccentric pin 49 passes through the eye 50 of said bolt to enable the ring sections to be drawn together. The pin 49 is journaled at its upper end to an apertured lug 51 and is likewise journaled at its lower end to a similar lug 52 and this pin may be turned by means of a hand-lever H attached to the shaft 49. In the modification shown by Fig. 1, the shaft 49 is, by means of a 105 coupling 53 attached to the lower end of a splined shaft 54 which extends upwardly in parallelism with the column and is journaled at its upper end to a lug 55 provided by the cap B'. The purpose of this is to enable the column to be clamped against 110 rotation by a hand lever J located at all times within the immediate reach of the user, i. e., on the drill-head D. To this end, a splined-shaft 56 is horizontally journaled 115 on the arm at points 57 and 58 and an oper-

ative connection between the shaft 56 and the vertical shaft 54 is established by bevel gears 59 which are likewise journaled on a part travelling with the arm. To enable the draw-bolt 46 to be adjusted, a nut 60 is secured on its end.

The portion 38 of the sleeve is split vertically at one side, as indicated by 74 on Fig. 5 and a bolt 61 enables the user so to 10 adjust the tension of the split portion that, when the split-ring M is contracted to seat the sleeve securely on the platform, it will simultaneously clamp the sleeve to the cylindrical portion 9 of the post. Preferably, 15 a dust-guard 62 in the nature of an annular ring or a flange will circumscribe the upper end of the split-ring and thereby prevent chips or dirt from getting into the contacting surfaces and impairing their accuracy 20 of operation. It is to be noted that the split-ring is located externally and is at all times accessible to the user of the machine and that it therefore admits of being very 25 easily disassembled and replaced after being cleaned or otherwise repaired.

It is desirable that the clamping-lever H should preserve its location relative to the sleeve B and to the radial-arm so that the user will not be put to the necessity of working 30 a lever located in unaccustomed relations. This object may, of course, be attained in diverse ways but it may be very simply achieved by providing an engagement between the ring M and the sleeve B 35 such that the ring cannot creep around the sleeve as a result of successive operations or be caused to be rotatably shifted in consequence of any manual efforts to turn the lever H. A pin 74 is shown set into the 40 sleeve and having its end 75 protruding into the space 76 between the contiguous ends of the portions m and m' of the split ring M. This pin will thus act as a means for restraining relative displacement between the 45 split ring and the sleeve, irrespective of the force applied to the lever H, and the user will hence always find the handle in the same relation to the vertical plane of the arm that he has become familiar with;

50 This clamping construction is not only of advantage in small-sized machines but also in radial drills of the more ponderous type. It has been found, in practice, to be exceedingly rigid and accurate when set or 55 locked while yet admitting of being thus locked by the mere application of ordinary manual power. Heretofore, for the purpose of locking the clamp in heavy-duty radial-drills, it has been quite difficult to do so effectively by an application of the limited 60 strength of an attendant and, therefore, such large machines have habitually embodied means for utilizing power for the purpose of setting the clamp. For example, attempts have been made to overcome this dif-

ficulty by constructing the clamp so that it may be operated by compressed air, or by power taken from some power-driving shaft through the agency of a friction-clutch, or else by power obtained electrically. These 70 complications may be altogether avoided by utilizing the fundamentals of construction herein set forth although, for special purposes, many or all of those features of construction may be utilized in a supplemental 75 and cooperative sense if an excessive degree of rigidity is desired.

It will be perceived that this clamp construction may, with equal facility, be resorted to either in that type of radial drill 80 in which the arm extends integrally from the sleeve and which, therefore, admits of being swung around a vertical pivot with the sleeve but does not provide for any vertical adjustment relative to the sleeve, or the 85 clamping mechanism may be applied to the more universal type of radial drill such, for example, as that indicated by the drawings.

As shown by Fig. 2, the elevation of the arm may be effected by power derived from 90 the base of the machine in the manner conventionally resorted to when the motor is located on the base. In that form, a horizontal shaft 63 enters the base through a side aperture and is connected, by means 95 of bevel-gears 64, so as to derive motion from a vertical shaft 65 passing through the axis of the post; said shaft being journaled at its lower end in a bearing 20 carried by the vanes 21 and at its upper end in a bushing 66 lining the bore of a bearing 15 provided by the upper end of the post. In constructions heretofore used, the bearing for the upper end of this shaft has been provided by a cap-member affixed to the upper 100 end of the sleeve but, in those previous constructions, there existed a tendency for the normal friction (between the rotating shaft and the cap) to swing the arm; which objection is, by the present construction, entirely obviated. In other words, the shaft 65 is journaled only on solid immovable portions of the fixed post A. This shaft 65 is 105 surmounted by a gear 67 which likewise rests upon a stationary bearing 19 formed by the extreme upper end of the post. From the gear 67, motion is obtained and is utilized through conventional instrumentalities for either driving the spindle or for raising or 110 lowering the arm. These parts being conventional need not be described.

To still further increase the smoothness of action of the sleeve when the clamp is released, the construction may include in combination the arrangement disclosed in the 115 co-pending application of D. C. Klausmeyer No. 480,653, filed June 27, 1921 and entitled "Arm mount with accessible gear unit"; in which case, the mechanism may to advantage 120 be built in accordance with Fig. 6. The 125 130

clamping surface 9^a is, in this case, shown sufficiently larger in diameter than the bearing surface 11 to provide room for an adjustable bearing and, intervening between the clamp-surface 9^a and bearing 11, is located an annular runway 80 which is preferably formed of a hardened steel ring 81 shrunk onto an annular seat 82 provided by the post. The sleeve B is formed as indicated by 83 and its interior annular surface is provided with a small hub 84 having a vertical hole 85 in which is seated a stud 86 terminating at its lower end in an eccentrically located portion 87 which carries a ball-bearing 88 which functions as a roller riding on the periphery 80 of the hardened ring 81. The end of the stud is headed, as indicated by 89, to keep the ball-bearing in place and a lock-screw 90 serves to hold the stud in place and prevent it from rotating. By releasing the lock-screw 90 and by applying a wrench to a squared socket 91 in the upper end of the stud 86, the latter may be turned sufficiently to cause the ball-bearing 88 to press laterally against the bearing 80 with sufficient force to compensate largely or wholly for the lateral thrust set up against the bearing-surface 11 as a result of the deflection of the sleeve under the turning-moment of the arm which radially extends therefrom in the vertical plane of the pressure-relieving device above explained. It is to be understood that this pressure-relieving device is not relied upon as a main-bearing for the sleeve but fundamentally for the purpose of sufficiently relieving the friction of the main-bearings so that, when the clamp M is released, the user of the machine can swing the ponderous sleeve and its massive radial arm about a horizontal arc with ease and facility. It is also to be noted that, in this case, the pressure-relieving device is so constructed that it will not interfere in any way with the slight up-and-down shifting of the sleeve caused by an operation of the clamp ring M, i. e. the roller 88 may slide vertically on its track 81 since the periphery 80 of the latter is truly cylindrical and has no shoulders and no such taper as would prevent an upward shift of the roller 88.

Without further analysis, the foregoing will so fully reveal the gist of this invention that others can, by applying current knowledge, readily adapt it for various utilizations by retaining one or more of the essential characteristics of either the generic or specific aspects of this invention, and, therefore, such adaptations should be, and are intended to be, comprehended within the meaning and range of equivalency of the following claims.

Having thus revealed this invention, we claim as new and desire to secure the following combinations and elements, or

equivalents thereof, by Letters Patent of the United States:

1. A mechanism of the nature disclosed combining a tubular member; an upright post extending through the bore of said tubular member and terminating adjacent the uppermost end thereof; a thrust-bearing intervening between the uppermost ends of said member and of said post; resilient means interposed between said thrust-bearing and one of said parts whereby a large portion of the weight of said tubular member may be carried by said thrust-bearing; said post being provided adjacent its lowermost end with an annular platform and said tubular member having an annular seat arranged in immediate proximity with said platform, said platform and said seat being in the nature of weight-supporting surfaces; and clamping means for depressing said tubular member firmly to said platform against the yielding opposition of said resilient means.

2. A mechanism of the nature disclosed combining a base and a non-rotatable post upstanding thereon; a tubular member suspended from the upper end of said post and having its lower portion circumscribing said post, said lower portion and the adjacent portion of said base being provided with co-acting bearing-surfaces located in a substantially horizontal plane; means for permitting a limited depression of said suspended tubular member; and a clamping device cooperating with said means for establishing a positive contact between the aforesaid bearing surfaces.

3. A mechanism of the nature disclosed combining an outer tubular member; a post substantially co-extensive in length with said member and extending upwardly through the bore thereof; a yielding thrust-bearing interposed between the upper ends of said post and member; said post and member having co-acting bearing surfaces adjacent their lower ends; and clamping means for positively depressing said member to establish a firm contact between said lower bearing surfaces.

4. A mechanism of the nature disclosed combining an upright post having adjacent its lower end a cylindrical bearing surface and also a transverse annular seating surface; a sleeve resiliently suspended from the upper portion of said post and having an enlarged lower end circumscribing said cylindrical surface and having another bearing surface adjacent said seating surface; and means for depressing said seating surfaces and to establish a clamping relation between said cylindrical surfaces.

5. A mechanism of the nature disclosed combining an internal post; a sleeve resiliently suspended from an upper portion of said post and circumscribing the major por-

- tion of said post, the lower portion of said sleeve and an adjacent portion of said post having annular conical flanges providing substantially co-planar contact-surfaces; 5 and a member having an interior V-shaped groove adapted to cooperate with the conical portions of said two flanges to establish a firm seating of said sleeve against the lower portion of said post.
10. 6. A post for radial drills consisting of a single casting in the nature of a tube, the lower end of said post being flared and the upper portion of said post having a smooth cylindrical periphery and having its entire 15 inner periphery continuously corrugated, certain of said corrugations being extended inwardly and downwardly beyond the other corrugations and supporting a shaft bearing.
15. 7. A post for radial drills comprehending a tube having its upper portion of substantially uniform diameter and its lower portion enlarged, the upper interior portion of said post being continuously corrugated 20 and the lower interior portion being provided with vanes radiating inwardly toward the center.
20. 8. A radial drill combining a post and a sleeve circumscribing said post; five bearings interposed between said post and sleeve, the uppermost and the lowermost bearing being adapted to sustain the weight of said sleeve, two of the remaining bearings serving to centralize the sleeve on said 25 post, the one bearing being near its upper end and the other near its lower end, and the remaining bearing being in the nature 30 of a cylindrical clamping surface.
25. 9. A radial drill combining a tubular post having its upper portion interiorly corrugated, said post having at its uppermost end a shoulder for seating a downward-thrust bearing and having also at its upper end an annular seat for a centering bearing, said 35 post having also near its lower end a cylindrical centering bearing and also a cylindrical clamping surface, said post having below the aforesaid bearings an annular weight-supporting platform; a sleeve circumscribing said post and having two interior smooth bearings adjacent its lower end and also an annular face adapted to be seated on said platform; a thrust-bearing interposed between the sleeve and the shoulder at the upper end of said post; and a roller-bearing for holding the upper end of the sleeve in co-axial action with said post.
30. 10. A radial drill combining a post and a sleeve circumscribing said post; means for mounting said sleeve to rotate about said post; and means for clamping said sleeve against rotation, both said sleeve and said post being tubular in form and both having the major portions of their interior surfaces 35 corrugated; said post being formed on its exterior surface with a plurality of cylindrical bearing surfaces, and said sleeve being provided with a like number of internal bearing surfaces extending inwardly beyond the corrugations of said sleeve and contacting with the bearing surfaces of said post.
11. A radial drill combining an upright post; a sleeve circumscribing said post; a thrust-bearing for supporting said sleeve and located at the upper end of said post; and a flexible annular diaphragm intervening between said thrust-bearing and said sleeve for resiliently supporting the latter.
12. A radial drill combining a post and a sleeve circumscribing said post; and yielding supported upon the upper end thereof; said sleeve and said post providing flanges presenting endwise abutment surfaces normally maintained in spaced relation, vertically disposed cylindrical clamping surfaces, and also conversely disposed conical surfaces, the inclusive angle of which is not greater than 90 degrees, and a clamping ring cooperating with said conical surfaces, to effect relative endwise movement between said post and sleeve to firmly engage said abutment surfaces and simultaneously therewith to effect a locking action between said vertically disposed clamping surfaces.
13. A radial drill combining a sleeve and a post, upon which said sleeve is yielding supported, said sleeve and post each having endwise abutment surfaces and flanges tapered at a greater angle than the angle of repose and less than 45 degrees to the line of lateral thrust; co-acting vertically disposed clamping surfaces provided by said sleeve and post; and means cooperating with said flanges and adapted to move in the line of lateral thrust to force said abutment surfaces together endwise, and simultaneously therewith effect a locking action between said clamping surfaces; the angles of the flanges and their cooperating means being such that the greater force is transmitted in a vertical direction.
14. A radial drill combining a post having a cylindrical clamping surface; a sleeve circumscribing said post and having a split portion around said cylindrical clamping surface, said sleeve and said post also having endwise abutment surfaces; and a wedgelike member adapted for lateral movement and having its acting surface inclined at an angle adapted simultaneously to move the adjacent portion of said sleeve both laterally and vertically.
15. A mechanism of the nature disclosed combining a tubular member; an upright post extending through the bore of said tubular member and terminating adjacent the uppermost end thereof; a thrust-bearing, intervening between the upper ends of said member and of said post;

5 a resilient diaphragm interposed between said thrust-bearing and one of said parts; an adjustable device between said diaphragm and said thrust-bearing adapted to regulate the normal position of said tubular-
10 member; said post being provided adjacent its lowermost end with an annular platform and said tubular member having an annular seating surface arranged in immediate proximity with said platform; and clamping means for depressing said tubular member firmly against said platform against the yielding opposition of said diaphragm.

15 16. A mechanism of the nature disclosed combining a base and a non-rotatable post upstanding thereon; a tubular member suspended from the upper end of said post and having its lower portion circumscribing said post, said lower portion and the adjacent portion of said base being provided with co-acting bearing-surfaces located in a substantially horizontal plane; an adjustable diaphragm for permitting a limited resilient depression of said suspended tubular member; and a clamping device operative against said diaphragm for establishing a positive contact between the aforesaid bearing surfaces.

20 30 17. A mechanism of the nature disclosed combining an outer tubular member; a post co-extensive in length with said member and extending upwardly through the bore thereof; a thrust-bearing interposed between the upper ends of said post and member; an adjustable resilient means between said thrust-bearing and said tubular-member; said post and member having co-acting bearing surfaces adjacent their lower ends; and clamping means for positively depressing said member to establish a firm contact between said lower bearing surfaces.

25 40 45 50 55 18. A mechanism of the nature disclosed combining an upright post having adjacent its lower end a cylindrical bearing surface and also a transverse annular seating surface; a sleeve resiliently suspended from the upper portion of said post and having an enlarged lower end circumscribing said cylindrical surface and having another bearing surface adjacent said seating surface; means for adjusting the normal position of suspension of said sleeve; means for depressing said sleeve to establish contact between said seating surfaces; and means to establish a clamping relation between said cylindrical surfaces.

60 65 19. A mechanism of the nature disclosed combining an internal post; a sleeve; adjustable means for resiliently suspending it from an upper portion of said post, said sleeve circumscribing the major portion of said post and the lower portion of said sleeve and an adjacent portion of said post having annular conical flanges providing substantially co-planar contact-surfaces; and

means having an interior V-shaped groove adapted to cooperate with the conical portions of said two flanges to establish a firm seating of said sleeve against the lower portion of said post.

70 20. A post for radial drills consisting of a single casting in the nature of a tube, the lower end of said post being flared and the upper portion of said post having a cylindrical periphery and having its inner periphery provided with a multiplicity of downwardly extending ribs in the nature of corrugations; a shaft-bearing supported by certain of said ribs the upper end of said post being formed with a reduced cylindrical portion formed with a central bore adapted to support a shaft-bearing; a horizontally disposed sleeve-supporting shoulder extending outwardly from said reduced portion and adjacent its lower end and terminating in a vertically disposed sleeve-locating bearing surface.

75 21. A post for radial drills comprehending a tube having its upper portion of substantially uniform diameter and its lower portion enlarged, the upper interior portion of said post being corrugated and the lower interior portion being provided with vanes radiating inwardly toward the center, the upper end of said post providing concentric bearing surfaces and at its lower end having a bearing to which said vanes are integrally connected.

80 85 90 95 100 105 22. A radial drill combining a post and a sleeve circumscribing said post; five bearings interposed between said post and sleeve, the uppermost and the lowermost bearing being adapted to sustain the weight of said sleeve, two of the remaining bearings serving to centralize the sleeve on said post, the one bearing being near its upper end and the other near its lower end, and the remaining bearing being in the nature of a cylindrical clamping surface; and a shaft extending through the bore of said post and journaled thereto at its upper and lower ends.

110 115 120 125 130 23. A radial drill combining an upright sleeve having a radial arm extending horizontally therefrom; a supporting column for said sleeve; means intermediate the column and sleeve; adapted to permit a slight depression of the sleeve; a drill-head shiftable horizontally along said radial arm; an operating lever mounted to be shifted into a position adjacent said drill head; clamping means for depressing said sleeve; and connections extending from said clamping means to said lever whereby the latter wherever located may be employed to actuate said clamping-means.

24. A radial drill combining a post and a sleeve circumscribing said post; said sleeve and said post providing flanges presenting endwise abutment surfaces and also con-

versely disposed conical surfaces; a clamping ring carried by and movable with said sleeve and cooperating with said conical surfaces, said ring having an engagement for 5 keeping it from shifting about said sleeve; and a lever for constricting said ring.

25. A radial drill combining a post having a cylindrical clamping surface; a sleeve circumscribing said post and having a split 10 portion around said cylindrical clamping surface, said sleeve and said post also having endwise abutment surfaces; a wedgelike annulus adapted for lateral movement and

having its acting surface inclined at an angle adapted simultaneously to move the 15 adjacent portion of said sleeve laterally and vertically, said annulus being interlocked to said sleeve to prevent it from shifting around said sleeve; and means mounted in fixed relation to said sleeve for constricting 20 said annulus.

In witness whereof, we hereunto subscribe our names:

DAVID C. KLAUSMEYER.
ROWLAND L. RICKWOOD.
